UNITED STATES PATENT OFFICE.

VERNER J. WAHLSTROM, OF BROOKLYN, NEW YORK.

COUPLING.

SPECIFICATION forming part of Letters Patent No. 771,951, dated October 11, 1904.

Application filed April 20, 1904. Serial No. 204,047. (No model.)

To all whom it may concern:

Be it known that I, VERNER J. WAHLSTROM, a citizen of the United States, residing at Brooklyn, in the county of Kings and State of New York, have invented a new and useful Coupling, of which the following is a specification.

This invention relates to an improvement in couplings; and the object thereof is to provide a simple, efficient, and inexpensive device adapted to this and other analogous purposes which is easily applied and in which there are no projecting flanges or bolts, sometimes the cause of serious accident.

15 The invention consists in certain constructions and combinations, which will be herein-after fully described and then specifically set forth in the claims hereunto appended.

In the accompanying drawings, which form 20 a part of this specification, and in which like characters of reference indicate the same parts, Figure 1 illustrates one form of device embodying the invention. Fig. 2 is a sectional view of the device illustrated in Fig. 1. 25 Fig. 3 is a cross-sectional view on the line 3-3 in Fig. 1.

30 In the operation of this invention a clamp may be arranged to be operated upon by a rotating shaft, a second clamp may be arranged to cause the rotation of a second shaft, and means may be provided for transmitting the motion of the first shaft through its clamp to the second clamp, which in turn will transmit the motion to the second shaft. This 35 means will be actuated by the first clamp and will operate to produce the action of the second clamp. Preferably, however, and as shown in the device illustrated in Figs. 1, 2, and 3 a plurality or set of clamps is provided

40 arranged to be simultaneously operated by a rotating shaft. These clamps may vary widely in construction; but, as shown, they are preferably cylindrical in form and are marked 5. The clamps 5 are in contact with the shaft 6, so that when the shaft is rotated, as in the direction indicated by the arrow in Fig. 3, the clamps will be moved or operated simultaneously by the shaft. A second set of clamps, 7, is preferably provided similar in construction to the clamps 5, and the clamps of this

second set are arranged to coöperate to cause the rotation of a second shaft 8, the tendency being when the clamps 7 are moved in contact with the shaft 8 to also move the shaft, thus causing its rotation. It is obvious that when the driving-shaft is reversed the clamps 5 will be moved on the cam-faces 10 until the sleeve 9 is freed from the shaft 6 and the shafts thereby uncoupled and that the shafts will remain uncoupled as long as the driving-shaft runs in a direction opposite to that indicated by the arrow in Fig. 3, the sleeve being arranged to remain inactive while the driving-shaft is running in a reversed direction.

45 In order to transmit the motion from the first shaft to the second shaft through the clamps, means are provided actuated by the first set of clamps and operating to produce the coöperating action of the second set of 50 clamps, and this means may be widely varied in construction. As shown, however, it consists in a sleeve 9, which is provided at one end with a plurality of eccentric cam-faces 10, each of said faces contacting with one of said 55 clamps 5. Similarly at its other end the sleeve 9 is provided with a plurality of eccentric cam-faces 11, each of said cam-faces contacting with one of the clamps 7. Preferably these sets of cam-faces are out of alinement, and, as shown, the cam-faces 10 at one end of the sleeve 9 are inclined in one direction and the cam-faces 11 at the other end of the sleeve 9 are inclined in the opposite direction. Preferably, and as shown, the sleeve 9 is provided with a wall 12, which separates the two 60 sets of clamps.

65 Means are provided for retaining the clamps and sleeve in position. As shown, this means consists in a pair of collars 13 14, the collar 13 being held on the shaft 6 by means of a set-screw 15 and the collar 14 being held on the shaft 8 by means of the set-screw 16.

70 In the operation of the device when the shaft 6 is rotated in the direction indicated by the arrow in Fig. 3 the clamps 5 will be operated by the shaft and caused to roll on the eccentric faces 10, where they become wedged and actuate the sleeve 9. The sleeve being 75 in contact with the clamps 7 operates to set 80

85 90 95 100

them in motion, rolling them on the eccentric faces 11 until they become wedged on the shaft 8, thus producing the coöperating action of the clamps 7, which causes the rotation 5 of the second shaft 8.

The invention is not to be restricted to the construction shown and described, as the construction may be widely varied without departing from the invention. The invention 10 may also be used for purposes other than the coupling of shafts, and such other use is contemplated.

What is claimed is —

1. In a coupling, the combination with a 15 clamp arranged to be operated by a driving-shaft, of a second clamp arranged to rotate a second shaft, and means normally actuated by the first clamp to produce a movement of said second clamp to rotate the second shaft, said 20 means being arranged to remain inactive while the driving-shaft is running in a reversed direction, substantially as described.

2. In a coupling, the combination with a set 25 of clamps arranged to be simultaneously operated by a driving-shaft, of a second set of clamps arranged to coöperate to rotate a second shaft, and means normally actuated by the first set of clamps to produce the coöperating 30 action of the second set of clamps, said means being arranged to remain inactive while the driving-shaft is running in a reversed direction, substantially as described.

3. In a coupling, the combination with a set 35 of clamps arranged to be simultaneously operated by a driving-shaft, of a second set of clamps arranged to coöperate to rotate a second shaft, and a sleeve normally actuated by the first set of clamps to produce the coöperating 40 action of the second set of clamps said sleeve being arranged to remain inactive while the driving-shaft is running in a reversed direction, substantially as described.

4. In a coupling, the combination with a set 45 of clamps arranged to be simultaneously operated by a driving-shaft, of a second set of clamps arranged to coöperate to rotate a second shaft, and a sleeve having two sets of eccentric cam-faces one set of cam-faces being

out of alinement with the other set of cam-faces said sleeve being normally actuated by the first set of clamps to produce the coöperating action of the second set of clamps said 50 sleeve being arranged to remain inactive while the driving-shaft is running in a reversed direction, substantially as described.

5. In a coupling, the combination with a set 55 of cylindrical clamps arranged to be simultaneously operated by a driving-shaft, of a second set of cylindrical clamps arranged to coöperate to rotate a second shaft, and a sleeve having at one end a set of eccentric cam-faces inclined in one direction each of said faces contacting with one of the first set of clamps and having at its other end a set of eccentric cam-faces inclined in the opposite direction each 60 of said faces contacting with one of the second set of clamps said sleeve being normally actuated by the first set of clamps to produce the coöperative action of the second set of clamps said 65 sleeve being arranged to remain inactive while the driving-shaft is running in a reversed direction, substantially as described.

6. In a coupling, the combination with a set 70 of cylindrical clamps arranged to be simultaneously operated by a driving-shaft, of a second set of cylindrical clamps arranged to coöperate to rotate a second shaft and a sleeve having at one end a set of eccentric cam-faces inclined in one direction and having at its 75 other end a set of eccentric cam-faces inclined in the opposite direction and being provided with a wall separating said sets of cam-faces said sleeve being normally actuated by the first set of clamps to produce the coöperating 80 action of the second set of clamps said sleeve being arranged to remain inactive while the driving-shaft is running in a reversed direction, substantially as described.

In testimony whereof I have signed my name to this specification in the presence of two sub- 85 scribing witnesses.

VERNER J. WAHLSTROM.
